UNITED STATES PATENT OFFICE.

JOHN W. SEIFERT, OF HOUSTON, TEXAS.

CLOSURE FOR REFRIGERATORS AND THE LIKE.

1,340,084.

Specification of Letters Patent.

Patented May 11, 1920.

Application filed March 28, 1918. Serial No. 225,377.

To all whom it may concern:

Be it known that I, JOHN W. SEIFERT, a citizen of the United States, residing at Houston, in the county of Harris and State of Texas, have invented new and useful Improvements in Closures for Refrigerators and the like, of which the following is a specification.

The object of the invention is to provide a simple and efficient construction of doors or lids for refrigerators, refrigerator cars, ice boxes, fireless cookers, telephone booths and the like, and as fire doors for storage houses, and wherever it is necessary or desirable to provide for facility of movement in opening and closing, unaffected by warping, swelling or shrinking, due to heat or cold, dampness or dryness, or other climatic or atmospheric or similar changes or conditions, while insuring an air tight, smoke, fire and bug proof, and heat insulating closure and seating joint, regardless of vibration of the receptacle on the door frame and of the size or shape of the door or lid.

Other objects and advantages will appear hereinafter in the description of certain substantial embodiment of the principle involved, it being submitted, however, that various changes in form, proportion, size and details of construction and specific arrangement of the essential elements may be resorted to in adaptation to the different contemplated uses, and within the scope of the appended claims, without departing from the spirit of the invention.

In the drawings,

Figure 1 is a front view of a door adapted especially for a refrigerator or refrigerator car, for use in a side wall opening thereof.

Fig. 2 is a horizontal sectional view of the same, showing in full lines the closed and in dotted lines the open positions of the parts, the plane of the section being indicated by the line 2—2 of Fig. 1.

Fig. 3 is a similar section on the plane indicated by the line 3—3 of Fig. 1.

Fig. 4 is a vertical section of a portion of the door on the line 4—4 of Fig. 1.

Fig. 5 is a horizontal section showing a double door arrangement.

Fig. 6 is a front view of the double door construction.

Fig. 7 is a detail view of the rocker rod.

Fig. 8 is a view of a supplemental member of a door showing the inside or housed surface thereof, the same being partly broken away to show the interior construction.

The closure embodying the invention is designed for use as a door or lid for adaptation to openings in either the top, bottom or side wall of a receptacle such as those named hereinbefore, consisting primarily of main and supplemental members 10 and 11, the latter of which is carried by the former and has a yielding relation therewith, both members being hollow, and it being preferred to arrange them in telescoping relations. As illustrated the main member 10 is hingedly mounted as shown at 12 and is provided with inwardly or rearwardly convergent walls 13 terminating in inturned flanges 14, while the supplemental member 11 is provided with parallel or perpendicular walls which terminate in outturned flanges 15 adapted for coöperation with the inturned flanges of the main member to constitute vertical stopping or limiting means for determining the extent of relative movement of the members in one direction, or more specifically the inward movement of the supplemental member under the impulse of spring elements 16 which are disposed and tensioned to exert a pressure serving to separate said members or advance the inner or supplemental member toward the closure seat 17 which is arranged in the path thereof and forms the base of the tapered door opening 18. The seat may be provided with a yielding cushion of felt or its equivalent as shown at 19, to increase the efficiency of the joint in preventing the passage of air or other medium, but primarily the yielding contact of the supplemental member with the seat is depended upon to insure a tight joint for the purposes herein set forth.

The supplemental member is preferably made of compartmental construction, having partitions 20 and provided with a filling 21 of asbestos or other fire insulating material, the partitions serving to hold the filling in place or prevent displacement thereof due to jar or the movement of the door, the inner or housed side of the supplemental member being fitted with a cover plate or partition 22 upon which is arranged a longitudinal rod 23 serving as one element of means for retracting the supplemental member or moving it relative to the main member to relieve the pressure of said supplemental member upon the seat of the door opening.

In the construction illustrated a rocker 24, consisting as shown of a shaft, is mounted upon and preferably exteriorly of the main

member and is provided with crank disks 25 having crank or wrist pins 26 with which are connected links 27 extending to and engaged with said rod on the supplemental member, said links extending through slots 28 in the inner or housed wall of the latter. Also preferably these links are slotted as shown at 29 so as to permit of a certain lost motion between the rocker and the supplemental member, so that when the closure is in its normal and locked position, the supplemental member is free for actuation solely by the springs, above described, which are arranged within the main member and bear against the inner or housed partition of the supplemental member. Obviously these links may be of any preferred construction and may be used in any desired number to suit the size and purposes of the particular closure.

In addition to the above described means the door is preferably provided with a lock which in the construction illustrated in Figs. 1 to 4 consists of a bolt 30 having an actuating spring 31 and adapted to engage a socket 32 in the wall of the door opening, and the rocker is provided with a toothed segment 32' for engagement with a rack 33 on said bolt whereby when the rocker is turned through the manipulation of a suitable handle 34, arranged at the outer side of the main member, to withdraw or relieve the pressure of the supplemental member upon the seat of the door opening, the bolt will be withdrawn from engagement with its socket against the tension of its actuating spring, so that the door may be swung to an open position by grasping a suitable grip 35. When it is desired to lock the door in its closed position the handle 34 may be provided with a slot 36 for engagement with a hasp 37 designed to receive a pad lock 38 or the equivalent thereof.

It will be obvious from the foregoing description that the specific means whereby connection is established between the rocker or the equivalent thereof and the supplemental member and the locking device, may be varied without detracting from the efficiency of the apparatus, but it is important, as a means of permitting the door to be opened and closed freely and without the exercise of any special effort on the part of the operator, as well as to insure proper seating regardless of any tendency of the parts to warp or swell or shrink, or become otherwise disturbed, that the devices for respectively retracting the supplemental member and bolt should be arranged in a timed relation so that when the door is closed it will be readily movable to its proper position while the supplemental member is in a retracted position, and that the release or movement of the locking device to its engaging position shall precede the release of

the supplemental member for its yielding engagement with the seat of the door opening. In the same way and for a corresponding reason, in the opening of the door the operation should be timed so that the first portion of the movement of the operating means shall retract the supplemental member to relieve its pressure upon the seat of the door opening, after which the bolt or locking device should be withdrawn to permit of the swinging or other opening movement of the closure. In the construction illustrated in Figs. 1 to 4 this timed relation between the operation of the two essential parts indicated is secured by the slotting of the links which serve as the connection between the rocker and the supplemental member, and the depression of the toothed segment on the rocker for engagement with the rack of the bolt, the locking movement of the rocker resulting in the engagement of the locking means and the release of the spring actuated supplemental member successively in the order indicated, while the unlocking movement of said rocker results in the withdrawal or retraction of the supplemental member and the disengagement of the locking means successively in the order indicated.

In the modified construction illustrated in Figs. 5 to 7, inclusive, a double door arrangement is indicated, the particular construction of each member of the same being substantially as hereinabove described, but one of the door sections is provided with a stop flange 38' to complete the seat necessary for the contact of the portion of the supplemental member which is adjacent to the point between the door sections, to insure a proper break-joint and hence prevent the circulation of air through the door opening. Also in this construction the rocker 39 is constructed in the form of a rock shaft having cranks 40 with which the links 41 for retracting the supplemental member are connected, said rocker being extended to the margins of the door and carrying the locking hooks or catches 41' for engagement with sockets 42 in the door frame or wall of the structure, this construction being similar to that now commonly employed in connection with doors of refrigerators and refrigerator cars. Obviously locking means similar to those hereinabove described may be employed to secure the rocker in that position which it assumes when the door has been closed and locked.

Having thus fully described my invention, I claim:

1. A closure for the purpose named comprising main and supplemental members and spring elements for yieldingly holding them in expanded relation, and manually operable means carried by one of said members for relatively moving said members in op-

position to the tendency of said spring elements.

2. A closure for the purpose named having a main member provided with locking means, a supplemental spring actuated seat engaging member, and common means carried by said main member for disengaging the locking means and retracting said supplemental member against the action of said 10 springs.

3. A closure for the purpose named having a main member provided with locking means, a supplemental spring actuated seat engaging member, and common manually 15 operable means carried by said main member for disengaging the locking means and retracting said supplemental member in successive steps.

4. A closure for the purpose named having main and supplemental relatively movable members, locking means for securing the main member in closed position, yielding means tensioned to impel the supplemental member toward the closure seat, and 25 manually operable releasing devices carried by one of said members for successively relieving the pressure of the supplemental member upon the seat and disengaging the locking means.

30 5. A closure for the purpose named comprising a pair of telescopically connected inner and outer relatively movable members, spring means between said members for normally holding the inner member projected, a rocker rod upon the outer member, crank elements carried by said rod and provided with wrist pins, links pivotally engaging said wrist pins and each having a lost motion pivotal connection with the 35 inner closure member, and a manually operable device for turning the rocker rod and shifting said links to retract the inner closure member against the resistance of the springs.

45 6. A closure for the purpose named having a main member provided with locking means, a supplemental spring actuated seat engaging member, a rocker mounted upon the main member and operatively connected 50 with said locking means, and slotted relative motion compensating links connecting the supplemental member with said rocker.

55 7. A closure for the purpose named having a main member provided with locking means, a supplemental spring actuated seat engaging member, said locking means consisting of a bolt, and common manually 60 operable means carried by the main member for disengaging the locking means and retracting said supplemental member against the resistance of its actuating springs, the same including a rocker having a toothed segment, and a rack on said locking bolt.

8. A closure for the purpose named comprising inner and outer telescopically connected closure members, springs between said members operating to hold the inner closure member yieldingly projected, a rocker rod upon the outer closure member, crank disks carried by said rod and provided with wrist pins, links pivotally engaging said pins and having a lost motion 65 70 75 80 85 90 95 100 105 110 115
